(57) **CLAIM**

The ornamental design for an event camera with post and base, as shown and described.

DESCRIPTION

FIG. 1 is a perspective view of an ornamental design for an event camera with post and base;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict portions of the event camera with post and base in which the design is embodied and form no part of the claimed design.
